UNITED STATES PATENT OFFICE.

THOMAS H. DUZAN, OF PALESTINE, TEXAS.

ADJUSTABLE ATTACHMENT FOR FREIGHT-CAR DOORS.

SPECIFICATION forming part of Letters Patent No. 354,973, dated December 28, 1886.

Application filed August 3, 1886 Serial No. 209,899. (No model.)

To all whom it may concern:

Be it known that I, THOMAS H. DUZAN, a citizen of the United States, residing at Palestine, in the county of Anderson and State of Texas, have invented certain new and useful Improvements in Adjustable Attachments for Freight Car Doors; and I do hereby declare the following to be a full, clear, and exact description of the invention, such as will enable others skilled in the art to which it appertains to make and use the same.

The object of this improvement is an adjustable attachment for freight-car doors, for preventing sparks and other objectionable matter from getting into the cars, and means for operating the attachment that is adapted for use in securing the door in different positions of adjustment, and for connection with the body of the car by means of a seal-support, in order that the fixed adjustment of the door cannot be changed without breaking the seal. These results are attainable by the mechanism illustrated in the drawings, herewith filed as part hereof, in which the same letters of reference denote the same parts in the different views.

Figure 1 represents a sectional side elevation of a freight-car and door provided with attachments embodying the features of my improvement. Fig. 2 is a transverse vertical section of the same, taken on the line $x-x$ of Fig. 1, and representing the parts adjusted for preventing sparks or other objectionable matter from getting into the cars. Fig. 3 is a transverse vertical sectional representation of a freight-car, taken on the same line as Fig. 2, and showing the parts in an adjusted position, adapted to the movement of the door. Fig. 4 is a sectional side elevation of a freight-car provided with my improvement, and representing the door adjusted to and secured in a position for ventilating the car and contents thereof. Fig. 5 is a sectional side elevation of a freight-car provided with my improved attachment in a modified form, adapted to the cars in present use. Figs. 6 and 7 are sectional detail representations, more fully illustrating the construction and relation of some of the parts. Figs. 9, 10, 11, and 12 are sectional detail representations more fully illustrating the relation of the parts shown therein.

A is the body of the car.

B is the car door, suspended from the side of the car by means of ordinary hangers, B' B', and slide C.

C' C² represent ordinary attachments to the lower part of the car-door and body of the car adjacent thereto, for securing the position of the door, independently of my improved attachment.

D is a cleat movably secured to the car-door, and connected with and adapted to be adjusted by an operating-handle, in a manner hereinafter fully explained.

D' D' represent bifurcated eye-plates, provided with countersunk perforations, for the reception of corresponding bolts or rivets, d, for connecting the plates to the cleat in a secure manner by the application of nuts or washers, and suitably clinching the same at the inside of either the cleat or bolt, as may be deemed advisable.

E E are studs secured to the car-door B by bolts or rivets d, substantially in the manner above set forth, for the plates fixed to the cleat D.

E' E' are link-plates suitably connected to the eye-plates D' and studs E E, as shown at f f', for equalizing the motion of the cleat D.

F is an eccentrically-formed casting fixed to the cleat D by bolts or rivets f² in the same manner as the eye-plates D', and provided with a corresponding slot. (Fully shown at f³ in Fig. 3.)

F' is a stud fixed to the car-door B by bolts or rivets d² in the same manner as the studs E E.

G is a lever or operating-handle pivoted to the stud F', as shown at g, adjacent to which it is provided with a rectangular extension (more fully shown in Fig. 10) for connecting the handle G with the eccentric frame F by means of a pin or wrist, G', set in a transverse perforation of and suitably secured to the lever-extension through the slot in the frame F. The outer end of the lever G is provided with a transversely-slotted bifurcated inward extension, (also fully shown in Fig. 10,) and adapted to fit over eyes or staples h h', suitably secured to the car-sill, and be connected thereto by a hook, H, inserted through the transverse slots in the lever-extension and through the staples or eyes h h'.

Fixed to the inside of the cleat D, as shown

in Fig. 3, is a metal plate, D², having an integral V-shaped or half-round projection, d⁴, which, when the cleat is adjusted, as shown in Figs. 1 and 4, enters corresponding grooves 5 at a' a² in the car-wall and prevents the longitudinal movement of the door. The side of the cleat D next to the car-wall is cut away at a slight inclination in a manner to cause the same to lean toward and bear against the edge 10 of the door when the cleat is moved against the car-wall by the operation of the lever G, and a jointure is thus attained that will effectively exclude the admission of sparks or other matter into the car.

15 My improvement may be adapted to the cars in present use by the modification shown in Figs. 5, 6, and 7, in which the car-wall is provided with half-round plates at K K', appropriately fixed thereto, and the cleat D is provided with 20 a groove, d⁵, for receiving the same when the parts are adjusted, as shown in Figs. 2, 4, 5. The car-wall should also be provided with a series of half-inch washers, or a plate of the same thickness adjacent to the slide C, as 25 shown at c³, and also a washer, d⁶, of similar thickness, adjacent to the end and lower edge of the door between the end of the latter and the plate K', in order to cause the door to clear the similar plate, K, when adjusted, as occasion 30 may require.

Bolted to the car-sill from the inside thereof and adjacent to the plate K' is an additional eye or staple, h', in position to be connected with the operating-handle G by the hook H, 35 which is provided with slots h², (fully shown in Fig. 9,) for the insertion of wire or tin strips for the application of a seal, H'.

To prevent loss the hook H should be connected by means of a chain (not shown) to the 40 handle G, or to the car door or wall, in a position adapted to its application, as shown, for connecting the handle G with either of the staples h h'.

The cleat D may be raised and lowered by 45 the handle G and the car-door adjusted either way, and by reason of the staple h' and groove a² the V-shaped projection of the cleat-plate inserted into the groove a², and the car-door thus be conveniently secured in a partly-open 50 position. This is often necessary to give ventilation to meat, vegetables, and other matter frequently shipped in box-cars, and with cars having doors of ordinary construction the doors are secured in partly-open positions by 55 means of strips nailed to the car-wall behind the door, and pieces from the door to the casing, to prevent the door from changing its position.

All cars loaded with cotton, hay, or other 60 combustible material require the car-walls to be provided with a cleat behind and immediately adjacent to the door, from the top to

the bottom of the latter, to prevent the admission of sparks and destruction of the contents of the car that would otherwise be likely 65 to accrue therefrom. When cars are thus cleated, the cleats must be nailed at the top, center, and bottom. This requires the person doing the cleating to have a ladder or get on top of the car to nail the cleat at the top 70 of the same, and often, owing to the surface of the ground where the cars are located, the cleats cannot be nailed at the center without using a ladder for reaching the part, unless the car is adjacent to a platform. By the improvement herewith illustrated these inconveniences and difficulties are entirely obviated, as all the desired results are quickly attained by the proper adjustment of the handle G, and securing the position of the same 80 by the hook and seal, as shown, and the seal, instead of being located at or near the longitudinal center of the car-door, as with the old-style hasps and fastenings now in use, is near the bottom of the car, where it is readily 85 accessible to conductors or others who are required to take record of the seals, which by the old construction is often a matter of difficulty when the cars are on level ground, and cannot be reached at all without the use of a 90 ladder when the car is located on a fill, and sometimes when the fills are high and steep there is no suitable support for a ladder, and the seals cannot be reached at all. By reason 95 of the seal being located as shown it is easily accessible under all circumstances.

Having explained the features of my improvement, what I claim as new, and desire to secure by Letters Patent, is—

1. In combination with the door and wall 100 of a freight-car, the cleat adjustably connected to the car-door in the manner set forth and adapted to engage with the car-wall, as shown and described, the operating-handle pivotally connected to the car-door and arranged to operate the cleat toward or away from the car-wall, and provided with a recessed extension for receiving a staple fixed to the car, and slots for receiving a locking-hook, and the locking-hook provided with recesses for the 105 reception of means for supporting a seal, substantially as specified, for the purpose set forth.

2. The combination, with a car-door, of the sliding cleat thereon, and the lever for operating said cleat secured to the car-door, the staples fixed to the car, the detachable hook, and means for supporting a seal on said hook, substantially as described.

In testimony whereof I affix my signature in presence of two witnesses.

THOMAS H. DUZAN.
